[57] **CLAIM**

The ornamental design for a safety stand for use in association with hydraulic lift, as shown and described.

DESCRIPTION

FIG. 1 is a right front perspective of a safety stand for use in association with hydraulic lift;

FIG. 2 is a front elevational view;

FIG. 3 is a left side elevational view;

FIG. 4 is a right side elevational view;

FIG. 5 is a rear elevational view;

FIG. 6 is a bottom plan view;

FIG. 7 is a top plan view;

FIG. 8 is a front elevational view as in FIG. 2, with the inner support tube in an alternate, vertically extended position; and,

FIG. 9 is a right front perspective view of a second embodiment of the safety stand for use in association with hydraulic lift, it being understood that the sole difference resides in the configuration of the base of the stand.
